UNITED STATES PATENT OFFICE.

PHILIP HILL, OF PHILADELPHIA, PENNSYLVANIA.

DESIGN FOR AN UMBRELLA-CARRIER.

SPECIFICATION forming part of Design No. 22,262, dated March 7, 1893.

Application filed January 14, 1893. Serial No. 458,388. Term of patent 3½ years.

To all whom it may concern:

Be it known that I, PHILIP HILL, a citizen of the United States, residing in the city and county of Philadelphia, State of Pennsylvania, 5 have invented and produced a new and original Design for Umbrella and Cane Carriers, of which the following is a specification, reference being had to the accompanying drawings, showing a part thereof.

10 The leading feature of my design for an umbrella and cane carrier is the binding strap of the same flaring from the ends toward the center.

15 Figure 1 represents a side elevation of a carrier embodying my design. Fig. 2 repre-

sents a perspective view thereof on an enlarged scale.

In the drawings:—A designates the binding straps, and B the carrying strap connected therewith. The straps A flare from the ends 20 C toward the center D, so that they may be said to widen from one end to the center, and then narrow from the center to the other end.

What I claim is—

The design for an umbrella and cane car- 25 rier, as shown and described.

PHILIP HILL.
